No. 11,455

October 7, 1879

UNITED STATES PATENT OFFICE.

LE ROY W. FAIRCHILD, OF NEW YORK, N. Y.

DESIGN FOR PENCIL-CASES.

Specification forming part of Design No. **11,455**, dated October 7, 1879; application filed September 6, 1879.
[Term of patent 7 years.]

To all whom it may concern:

Be it known that I, LE ROY W. FAIRCHILD, of the city, county, and State of New York, have produced a new and original Design for a Case for a Small Implement, of which the following is a full, clear, and exact description, reference being had to the accompanying engraved illustration, making a part of this specification.

The design in question relates to that class of ornaments usually denominated "watch-charms."

A represents the entire design. b is a ring. c is the eye in which the ring b is loosely held. d d' are ornamental beads, in imitation of cords, near the two ends of the shell. e e are longitudinal side bars or reeds, represented as bound together by the cords d d'. f is the

body of the case, between the side bars or reeds e e, in the form of a mat of braided reeds. g is the figure of a frog in relief.

These various parts, which together make up said design, may be shown in various colors, or different shades of the same color, if desired.

What I claim as my invention is—

A design for a small-implement case consisting of the tubular case having the configurative imitation of reeds bound and braided together, and the figure of a frog, substantially as shown and described.

LE ROY W. FAIRCHILD.
